UNITED STATES PATENT OFFICE.

EDWARD T. SCHOONMAKER, OF FORDHAM, NEW YORK, ASSIGNOR TO PEER-LESS MANUFACTURING COMPANY, OF LOUISVILLE, KENTUCKY, A CORPORATION OF DELAWARE.

DESIGN FOR A FIREPLACE-FRONT.

SPECIFICATION forming part of Design No. 35,383, dated December 3, 1901.

Application filed October 19, 1901. Serial No. 79,309. Term of patent 3½ years.

To all whom it may concern:

Be it known that I, EDWARD T. SCHOON-MAKER, a citizen of the United States, residing at Fordham, in the county of New York and State of New York, have invented and produced a certain new and original Design for Fireplace-Fronts, (Case A,) of which the following is a full, clear, and exact description.

10 This invention relates to what is known on the market as a "fireplace-front."

In the accompanying drawing, forming part of this specification, the invention is illustrated in front elevation.

15 As shown in the drawing, the leading or material feature of my design consists of a frame the sides of which are provided with a figure consisting of crossed trumpets encircled by a wreath and overlying a scroll and entwined 20 with a vine, all in high relief. The cross-piece has a central ornament, composed of crossed torches encircled by a wreath and entwined with a vine. The corners at the intersection of the uprights or sides and the 25 cross-piece have ornaments composed of a

wreath laid over a vine, or branches and streamers, which streamers extend into the sides and cross-piece. The top of the cross-piece has a crenelated molding, and the sides and cross-piece are bordered with parallel 30 lines of beads and a crepe-like ornamentation. The summer-front or center piece has as its central figure a representation, in relief and on a plain background, of a well-known work of art, inclosed by a circular fluted and 35 beaded border. The background other than as described is stippled or made to present a granular surface.

Having thus described my invention, what I claim as new, and desire to secure by Letters 40 Patent, is—

The design for a fireplace-front, substantially as shown and described.

In testimony whereof I have hereunto set my hand this 14th day of October, A. D. 1901. 45

EDWARD T. SCHOONMAKER.
